(57) **CLAIM**

The ornamental design for a backless plunge support bra with shoulder straps, as shown and described.

DESCRIPTION

FIG. 1 shows a front perspective view of a backless plunge support bra with shoulder straps showing our new design; FIG. 2 shows a front view thereof;

FIG. 3 shows a rear view thereof;

FIG. 4 shows a left side elevation view thereof;

FIG. 5 shows a right side elevation view thereof;

FIG. 6 shows a top plan view thereof; and,

FIG. 7 shows a bottom plan view thereof.

The broken lines in the drawings illustrate environmental subject matter and form no part of the claimed design.
